UNITED STATES PATENT OFFICE.

KEITH M. HALL, OF LAC DU FLAMBEAU, WISCONSIN.

PHONOGRAPH RECORD.

Application filed October 9, 1928. Serial No. 140,521.

This invention relates to phonograph records or the like and cabinets for containing the same.

An important object of the invention is to provide phonograph records or like articles provided with index tabs whereby the articles may be stored in close parallel relation and may be identified without removing them from the storage container or cabinet.

A further object is to provide a phonograph record or like article provided with a flexible tab which is adapted to be flexed from normal position to permit the reading of the tab of the next adjacent phonograph record in a cabinet or the like.

A further object is to provide an identification tab which is adapted to be embedded in and to project from the edge of a phonograph record or the like whereby the records may be stored in a suitable cabinet and may be readily identified without removing them from the cabinet to permit the reading of the center labels usually provided thereon.

A further object is to provide an index tab of the above mentioned character which is adapted to be embedded in articles formed of plastic compositions, and wherein the tab is provided in the embedded portion thereof with perforations or the like whereby the material of the article will firmly hold a tab in position.

A further object is to provide a novel form of cabinet adapted for use with the articles having the tabs thereon.

Other objects and advantages of the invention will be apparent during the course of the following description.

In the drawings, I have shown several embodiments of the invention. In this showing,

Figure 1 is a side elevation of a cabinet containing a number of phonograph records or the like, parts being shown in section,

Figure 2 is a sectional perspective of the cabinet showing one of the records being withdrawn therefrom,

Figure 3 is a fragmentary sectional view of a portion of a phonograph record showing the tab as applied thereto,

Figure 4 is a fragmentary perspective of a portion of a modified form of cabinet, and

Figure 5 is a fragmentary side eleva-

tion of the device as viewed from one side of a double faced phonograph record.

Referring to the drawings, the numeral 10 designates a phonograph record of the usual type having sound grooves 11 thereon and provided with a central identification label 12. These records are made in single faced form, and also in double faced form, having sound grooves 13 on the opposite side as shown in Figure 5.

An index tab 14 is employed for identifying the individual records in a manner to be described. In practice, the tabs are preferably formed of a suitable flexible material such as celluloid or the like, which is adapted to retain a normal shape and which may be flexed from such normal shape when desired. The inner end of the tab 14 is provided with openings or perforations 15 as indicated in Figures 3 and 5. As is well known, phonograph records are made of plastic materials and the perforated ends of the tabs are adapted to be arranged in the material of the records prior to the hardening and finishing thereof. It will be apparent that the materials of the record flow through the perforations of the tab thus securely holding the latter. The tab is provided with an indicia bearing portion 16 extending from one edge thereof, and this projecting portion is provided on one side with suitable indicia 17 whereby the record may be identified. When the device is employed in connection with a single faced record, the indicia is printed on the record in such a manner that it is viewed right side up when the tab is arranged at the top of the record, as shown in Figure 2. When the device is used in connection with double faced records, the opposite side of the tab is provided with suitable indicia 18 which is printed upside down, for a purpose to be described.

In Figures 1 and 2 of the drawings, I have shown a suitable cabinet 19 adapted to hold the records. This cabinet is provided with a bottom 20 and side walls 21, and is divided throughout its length by suitable relatively thin partitions 22 which terminate below the upper end of the cabinet as shown. The partitions 22 provide spaces for the reception of the phonograph records, and the latter are placed in position in the cabinet with the tabs extending upwardly.

The cabinets are preferably made according to the size of the records to be placed therein, and the partitions are of such a height that the upper ends of the tabs will project upwardly a substantial distance beyond the partitions. If desired a suitable record receiving cabinet 23 may be built into a phonograph 24 as shown in Figure 4. This cabinet is shown as being provided with angularly arranged forward and rear walls 24 and 25 respectively and the cabinet is provided with partitions (not shown) similar to those previously described.

The operation of the device is as follows: 15 The records are placed in successive spaces between the partitions of either cabinet and are preferably arranged with the indicia 17 facing in the same direction. When it is desired to select a record from the cabinet, 20 the fore finger may be moved progressively along the tabs as shown in Figure 1. As each successive tab is bent downwardly, the preceding tab readily may be read, while the reverse sides of the tabs may be read 25 while the tab is held downwardly in the position shown in Figure 1. When the tabs are held in this position, the indicia 18 may be read right side up as will be apparent. By employing material of the character of 30 celluloid or the like, the tabs normally lie in the planes of their respective records, and when flexed and released will return to such normal positions. Thus it will be apparent that no index cards are necessary for 35 properly indexing the records, and it is wholly unnecessary to remove a record to read the center label thereon. A selected record readily may be removed from the

cabinet by grasping the tab thereof between the thumb and fore finger as indicated in 40 Figure 2.

The tabs may be suitably colored according to the type of record with which it is associated. For instance, popular music may be indicated by the color red on the 45 tabs, vocal music by the color blue, etc. The user then may readily select the type of music which is desired to play.

It is to be understood that the forms of the invention herewith shown and described 50 are to be taken as preferred examples of the same, and that various changes in the shape, size, and arrangement of parts may be resorted to without departing from the spirit 55 of the invention or the scope of the subjoined claims.

I claim:

1. A phonograph record comprising a relatively thin rigid body, and a flexible tab having an inner portion embedded in 60 said body and an outer portion extending outwardly from one edge thereof, the embedded portion of said tab having openings therein into which the material of said body extends. 65

2. A phonograph record comprising a relatively thin rigid circular body formed of plastic material, and a flexible tab substantially thinner than said body and having an inner portion embedded therein substantially centrally of its thickness and an outer 70 portion extending outwardly from one edge thereof.

In testimony whereof I affix my signature.

KEITH M. HALL.
